UNITED STATES PATENT OFFICE.

GEORGE C. DIVRY, OF NEW YORK, N. Y.

TYPE-CASTING MOLD.

Application filed September 1, 1922. Serial No. 585,696.

To all whom it may concern:

Be it known that I, GEORGE C. DIVRY, a subject of the King of Greece, residing at New York, in the county of New York and State of New York, have invented new and useful Improvements in Type-Casting Molds, of which the following is a specification.

This invention relates to slug casting molds for use in connection with type casting machines and the invention is particularly directed to means for casting what I will refer to as low ribless slugs.

In slug casting machines, it is a well known custom to cast ribbed slugs which when cut are thicker at the top than at the bottom, and their evenness secured by afterwards trimming the ribs, cutting the same away more at their top portions than along their lower portions. In the case of ribbed slugs when it is desired to use same next to loose type, around boxes or as column rules, it is impossible to provide same with smooth surfaces against the material they come in contact with.

It is an object of my invention to provide an attachment for use in connection with the present well known molds wherein the usual form of mold cap and liners may be employed without loss of time or requirement of changes or other adjustments and associated with my attachment to form a low ribless slug which will be of uniform thickness throughout.

A still further object of my invention is to provide means for casting a ribless low slug of even thickness which will not work up in printing as is the case with high slugs and one which can be cut into labor saving sizes and used in composition next to loose type, or as quads, etc., while being generally useful as a spacing material for all purposes.

A still further object of my invention is to provide an attachment of the character specified wherein no time is lost in applying same to an ordinary mold.

A still further object of my invention is to provide an attachment for ordinary forms of molds wherein an even ribless slug is formed and provided with a straight face and base, the attachment being constructed whereby the molded slug is held against being drawn backwards by the retreating mouthpiece after the casting operation and thereby held against being overtrimmed by the back knife, which further prevents the

slug from being trimmed less than the desired height.

With the above and other objects in view which will appear as the nature of the invention is better understood, the same consists in the improved construction and novel arrangements of parts which will herein-after be fully described and particularly pointed out in the claims.

In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1, is a perspective view of a mold showing its parts separated and locking toward the under face of the mold cap, my improved attachment being illustrated between the cap and base of the mold.

Figure 2, is a transverse section through the mold when locked showing my attachment operatively arranged between the sections of the mold for casting a low-ribless slug.

Figure 3, is a perspective view of a cast slug.

Figure 4, is a transverse section through the slug, and

Figure 5, is a plan view of a modified form of plate for casting a high slug.

In carrying the invention into practice, use is made of a well known mold 10 which includes a lower section 11 and a cap section 11^a, the former provided with slightly tapered liners 12—12 and vertical end pins 13—13. These pins 13—13 are extended through the slots 14—14 in the ends of the cap section 11^a, so that the cap section of the mold can firmly and uniformly clamp against the base section 11 when the mold is set up ready for the casting operation. The mold cap 11^a, is provided upon its under surface with grooves 15, which when the mold is used without my invention will form spaced parallel tapered ribs upon one surface of the cast slug.

My attachment which I have incorporated in a mold of the above type for forming ribless slugs of uniform thickness designated in Figures 3 and 4 by the letter A consists of a flat steel plate 16 interposed between the liners 12—12 and the cap section 11^a, and provided on its under side near one of its

longitudinal edges with a depending ridge 17 which extends into the mold cavity and as shown, the ends of this ridge rest directly upon the liners 12-12. This plate serves to close against the grooved face of the cap section 11^a, of the mold and as illustrated, the ends of the plate are notched at 18-18 to accommodate the pins 13-13 and to co-act therewith so that the plate is uniformly positioned between the sections with the edge 19 thereof flush with the inner surface of the mold. The opposite edge of the plate is slotted longitudinally between its ends at 19^a, so that this edge comes slightly inwardly of the outer surface of the mold. When the plate 16 is arranged in the mold as described the ridge 17 serves through the fact that it rests upon the reduced ends of the aforesaid liners 12-12 to space the plate from the upper surface of the section 11 so that the mold cavity will be of a uniform depth throughout. The mold cavity is thus partly defined by the upper surface of the section 11 of the mold and the under surface of the plate 16 between the liners 12-12. The rear side of the mold cavity is adapted to receive the molten metal in the usual manner.

In order to close the opposite side of the mold, I employ a slide member 20 formed of brass and provided with a ridge 21, adapted to enter the mold cavity between the ends of the slot 19^a. The upper surface of this ridge is beveled downwardly and inwardly at 20^a, toward the cavity of the mold so that it will freely engage with the mold cap 11^a. The member is provided with spring portions 22-22 adapted to permit the member to yield slightly when the cap 40 of the mold is brought against the beveled surface 20^a, of said member. It will of course be understood that the member 20 is carried by the usual matrix block 23, and the spring portions 22, 22 co-act with the wall 45 24 of a dove tail slot 25 formed in the matrix block to removably secure the slide member thereto.

On reference to Figure 2, of the drawing, it will be observed that the grooves 15 in the cap section 11^a, are gradually of an increasing depth from one end toward the other end thereof and when the mold is used without my invention, the cast slug will be provided with tapered ribs. Incident to the provision of these ribs, the slug is of a greater thickness toward one side.

With my invention, I am able to employ the present form of mold and cast therefrom slugs of even thickness. No trimming or cutting down of the slug sections are required.

In Figure 5, I show a plate 21, of uniform width except at its ends. The said ends are notched at 22^a to accommodate the aforesaid pins 13-13. The width of this plate

is co-extensive with the width of the mold cavity. The plate is otherwise the same as plate 16 and by means thereof a high slug of uniform thickness may be cast.

From the construction of the member 20, the ridge 21 normally clears the upper surface of the section 11 of the mold and when the mold advances during the casting operation, the base of the ridge 21 is brought to bear against said upper surface of the section 11 through engagement of the tapered surface 20^a, with the mold cap 11^a. In this manner, I am able to produce a low slug which will be clean and uniformly even.

What I claim is:—

1. In casting mechanism of the class described, a sectional mold, a plate supported by the liners of one section and closing against an adjacent face of the other section of the mold and a ridge formed on said plate and extending into the cavity of the mold.

2. In casting mechanism of the class described, a sectional mold, a plate supported by the liners of one section and closing against an adjacent face of the other section of the mold and a ridge formed on said plate and extending into the cavity of the mold, said ridge occupying a position near one edge of said plate.

3. In casting mechanism of the class described, a sectional mold, a plate supported by the liners of one section and closing against an adjacent face of the other section of the mold, said plate and the liner-carrying section of the mold defining a mold cavity, and means closing against one side of the cavity and bearing against the plate and against the liner carrying section of the mold during the casting operation.

4. In casting mechanism of the class described, a sectional mold, a plate supported by the liners of one section and closing against an adjacent face of the other section of the mold, said plate and the liner-carrying section of the mold defining a mold cavity, means closing against one side of the cavity and yieldingly bearing against the plate and against the liner carrying section of the mold during the casting operation.

5. In mechanism for casting slugs of uniform thickness through the agency of a mold of the type employed for casting ribbed slugs, the combination with a sectional mold including a base section and a cap having a grooved face wherein the grooves thereof normally open to the cavity of the mold, of a plate closing against the grooved face of the cap and co-acting with the base section to close the grooves from said cavity.

6. In mechanism for casting slugs of uniform thickness through the agency of a mold of the type employed for casting ribbed slugs, the combination with a sec-

tional mold including a base section and a cap having a grooved face wherein the grooves thereof normally open to the cavity of the cap and co-acting with the base section to close the grooves from said cavity and a depending ridge formed on said plate and extending into said cavity.

7. In mechanism for casting slugs of uniform thickness through the agency of a mold of the type employed for casting ribbed slugs, the combination with a sectional mold including a base section and a cap having a grooved face wherein the grooves thereof normally open to the cavity of the cap and co-acting with the base section to close the grooves from said cavity and a depending ridge formed on said plate and extending into said cavity, and disposed near one edge of said plate.
8. The combination with a mold normally constructed to cast slugs of varying thickness toward one edge of the slug and including relatively separable mold sections, one

of said sections having grooves varying in depth toward one side of said section, of a plate closing the grooves and co-acting with the liners of the mold to support the plate in parallel relation to the other section of the mold, and means on the plate extending into the mold cavity for arresting movement of the casted slugs from the cavity in one direction after the casting operation.

9. As a new article of manufacture, a mold attachment for use in connection with sectional slug casting molds, a flat plate adapted to be interposed between the sections of the mold and to close against one of said sections and to co-act with the other section to complete the cavity of the mold when the sections are locked and depending means formed on the under side of said plate.

In testimony whereof I have affixed my signature.

GEORGE C. DIVRY.
